UNITED STATES PATENT OFFICE.

PHILO O. DERBYSHIRE, OF CHICAGO, ILLINOIS, ASSIGNOR TO THE DELAWARE CHAIR COMPANY, OF DELAWARE, OHIO, A CORPORATION OF OHIO.

COMBINED SCHOOL DESK AND CHAIR.

1,385,432.

Specification of Letters Patent. Patented July 26, 1921.

Application filed February 21, 1921. Serial No. 446,979.

To all whom it may concern:

Be it known that I, PHILO O. DERBYSHIRE, a citizen of the United States of America, residing at Chicago, Cook county, Illinois, have invented certain new and useful Improvements in Combined School Desks and Chairs, of which the following is a full, clear, and exact description.

This invention relates to a combined desk and chair for use in schools, classrooms, lecture-rooms, etc., and its chief object is to provide a combined desk and chair in which the desk portion can be adjusted vertically, horizontally and angularly, to make it convenient and comfortable to the occupant. Another object is to provide a chair-desk of the kind indicated, in which the desk portion is composed of two parts, one hinged to the other and normally occupying a generally horizontal position but capable of being swung upwardly to afford convenient and quick ingress and egress of the occupant. A further object is to provide a chair-desk of simple and substantial construction, which can be manufactured and sold at a low price. To these and other ends the invention consists in the novel features hereinafter described.

One form of the invention is illustrated in the accompanying drawings, in which—

Figure 1 is a perspective view of the complete device.

Fig. 2 is a rear view of the portion constituting the desk-top, and

Fig. 3 is a side view of the same.

Fig. 4 is a side view of the upper end of the desk-post or standard.

Fig. 5 is a perspective view of the two parts of one of the hinges used in the desk-top.

Figs. 6 and 7 are detail sectional views on lines 6—6 and 7—7, respectively, of Fig. 1.

Fig. 8 is a horizontal section of one of the hinges, on line 8—8 of Fig. 1.

In the particular embodiment illustrated, the chair has its seat 10, Fig. 1, extended forwardly at the right to form a horizontal arm or support 11, and the lower rung on the same side extends through the leg 12 to form a similar support 13. To these supports is secured a vertical post or standard in the form of a board 14 of suitable width and height, the lower end of which may be cut away at the rear, as shown, to form a foot 15. The standard may be secured to

the supports 11, 13, in any convenient manner, as by means of screws or bolts 16, 17. In the upper portion of the standard are two relatively large apertures 18, 19, located side by side as shown in Fig. 4, the purpose and function of which will be described herein-after.

In front of the chair and above the standard 14 is a substantial top 20, which overhangs the standard at the side thereof and is adjustably mounted thereon by means of a pair of flat clamping members 21, 22, preferably made of tough, spring wood, spaced apart the thickness of the standard by a spacing strip or batten 23 between the two. An angle-iron bracket 24 on the outside of the clamp, and one or more shelf-brackets 25 on the inside, insure adequate rigidity of the top on its support, as will be readily understood.

On the outer and inner sides of the supporting clamp 21—22 are two metal binding plates, 26, 27, and through these extend two binding bolts 28, passing through the apertures 18, 19 in the standard 14 and equipped at their outer ends with hand-nuts 29 of convenient size to be tightened or loosened by hand. The relative size and location of the bolts and apertures are such that when the clamp is loosened by unscrewing the hand-nuts 29 the entire top assembly can be shifted forwardly or rearwardly, and up or down, and also may be tilted angularly, to accommodate the occupant of the chair, after which the whole can be firmly secured in adjusted position by tightening the nuts 29, as will be readily understood.

The desk or top is made in two parts or sections arranged edge to edge, the rear part 30 being pivotally connected to the relatively fixed front part 20 by means of a hinge at each end. In the preferred form each hinge comprises an elongated member 31 of heavy sheet metal, having a flange 32 which underlies the end edge of the top section 30 and is secured thereto by bolts or screws 33. The enlarged end of the hinge member overlaps the adjacent edge of the top 20 and has an arc-shaped slot 34. The other hinge member 35, also made of heavy sheet metal, has a flange 36 which underlies and is secured to the edge of the top-section 20, as by means of bolts or screws 37. The enlarged end of the latter hinge member is provided with a stamped lug 38, which extends into the arc-

shaped slot 34 and serves as a stop to limit the downward swing of the section 30, as will be readily understood. Preferably the parts are so proportioned and arranged that 5 when the swinging section is in its lowermost position, as determined by the slot and stop, its upper surface is in the same plane as the upper surface of the fixed section 20. At any time, however, the former can be 10 swung up to practically a vertical position, to permit easy ingress and egress of the occupant. The hinge members are pivotally connected by any suitable means, as a stout bolt 39, at the center of curvature of the arc-shaped slot 34.

The space below the chair seat may be boxed in, as indicated in Fig. 1, to accommodate a deep drawer 40.

It will be observed that the embodiment 20 illustrated is simple in construction and that its working parts are few and little liable to derangement. It can be made almost entirely of wood, without sacrifice of strength, and the metal parts employed are well 25 adapted to withstand the stresses to which they are subjected in use.

It is to be understood that the invention is not limited to the construction herein specifically illustrated and described but can be 30 embodied in other forms without departure from its spirit.

I claim:

1. In a combined chair and desk, in combination, a chair; a flat standard secured to

the chair at the front and side thereof, having in its upper portion a pair of apertures located side by side; a transversely extending horizontal top above the standard and in front of the chair; a pair of flat clamping members depending from the underside of 40 and secured to the top and embracing the apertured upper portion of the standard; and a pair of clamping bolts extending through the clamping members and the apertures in the standard, said apertures 45 being larger than the bolts to permit horizontal, vertical and angular adjustment of the clamping members to vary the horizontal, vertical and angular positions of the top. 50

2. In a combined chair and desk, in combination, a chair; a flat standard secured to the chair at the front and side thereof, a horizontal top above the standard and in front of the chair, comprising a relatively 55 fixed section and a movable section pivotally connected to the relatively fixed section at the rear edge thereof; a pair of flat clamping members depending from the relatively fixed section of the top and secured thereto, 60 and embracing the upper portion of the standard; and means for binding said clamping members upon the standard and permitting vertical, horizontal and angular adjustment of the said top. 65

In testimony whereof I hereunto affix my signature:

PHILO O. DERBYSHIRE.
